UNITED STATES PATENT OFFICE.

JAMES R. MOFFATT AND RALPH S. KELSO, OF CHICAGO, ILLINOIS, ASSIGNORS TO UNION SPECIAL MACHINE COMPANY, OF CHICAGO, ILLINOIS, A CORPORATION OF ILLINOIS.

SEWING-MACHINE.

1,157,891.

Specification of Letters Patent. Patented Oct. 26, 1915.

Application filed November 4, 1911. Serial No. 653,564.

To all whom it may concern:

Be it known that we, JAMES R. MOFFATT and RALPH S. KELSO, citizens of the United States, residing at Chicago, in the county of Cook, State of Illinois, have invented certain new and useful Improvements in Sewing-Machines, of which the following is a description, reference being had to the accompanying drawing and to the letters and figures of reference marked thereon.

The invention relates to new and useful improvements in sewing machines, and more especially to multiple needle chain stitch sewing machines.

15 An object of the invention is to provide a needle guard which may be moved into engagement with the needle in the rear thereof, so as to prevent the needle from being deflected and struck by the looper, which needle guard is so operated as to partake of all the movements of the looper.

20 A further object of the invention is to provide a needle guard of the above character, which is so constructed as to engage the needle in the rear side thereof to prevent the deflecting of the needle when it is operating to draw up the previous needle loops shed from the looper.

25 A further object of the invention is to provide a multiple needle machine, wherein the needles are arranged diagonally to the line of feed, so that a plurality of loopers moving transversely of the line of feed may coöperate with the needles, with needle guards which partake of all the movements 30 of the looper and engage the needle at the rear side thereof, both on the forward and the backward movements of the loopers, and prevent any deflection of the needles, so that 35 the same will be struck by the loopers and prevent any deflection of the needles during the drawing up of the needle loops, as they 40 are shed from the loopers.

These and other objects will in part be 45 obvious, and will in part be hereinafter more fully described.

In the drawings which show by way of illustration one embodiment of the invention,—Figure 1 is a front view of a sewing 50 machine embodying my improvements, the work support being removed; Fig. 2 is a top plan view of the parts directly beneath the work support, the feed dog being removed for the sake of clearness; Fig. 3 is a 55 vertical sectional view on the line 3—3 of

Fig. 2; Fig. 4 is an enlarged detail in side view, showing the position of the loopers and needle guards at the time when the loopers are entering the needle loops; Fig. 5 is a plan view of the same; Fig. 6 is an 60 enlarged detail view, showing the position of the needle guards and the looper at the time when the needle loop is being shed from the looper and the needle is operating to draw up the same close to the other side 65 of the work; Fig. 7 is a plan view of the same, and in this view the position of the needle and looper thread in connection with one looper is shown; Fig. 8 is a diagrammatic view, showing the position of the needle guards, the loopers and needles on the down stroke of the needles; and Fig. 9 is a similar view, showing the position of the parts on the up stroke of the needles.

In the drawings, the invention is shown 75 as applied to a sewing machine consisting of a bed plate 1, from which rises a standard 2 having an overhanging arm 3.

Reciprocating in the overhanging arm 3 is a needle bar 4, carrying a plurality of 80 needles 5. These needles, as herein shown, are arranged in a line diagonally of the line of feed (see Fig. 2). The needle bar 4 is reciprocated from the usual needle lever 6, which in turn is vibrated by a link 7 connected to an eccentric on the main shaft 8. Coöoperating with each needle is a looper. The looper 9 coöperates with the left hand outside needle. The looper 10 coöperates with the middle needle, and the looper 11 coöperates with the right hand outside needle. These loopers are mounted on a single carrier 12, which is pivoted to a looper rocker 13, mounted in suitable bearings in brackets carried by the bed plate 1. The looper 95 rocker 12 is oscillated through an arm 14, which engages an eccentric on the main shaft 8. The looper carrier is vibrated on its pivotal support by a link 15, which is pivoted to the lower end of the needle lever 100 extension 16. These parts are of the usual construction in a chain stitch machine, and will not need further description.

The feed dog 25 is carried by the usual feed bar 26, which is raised and lowered by a cam 27, and is moved back and forth from a connection at the forward end of the main shaft of the machine. This feeding mechanism; also the controlling devices for the looper threads, and the controlling devices 110

for the needle threads, are of the usual type and will not need further description.

The looper-operating mechanism, as is usual in this type of machine, causes the looper to move forward into the needle loop, and thence laterally, in order to avoid the needle, so that the needle may on its down stroke enter the "thread triangle" formed by the needle loop of the previous stitch 10 around the looper, the looper body and the looper thread running from the eye of the looper to the previous stitch.

It is customary in this type of machine to so control the tension on the needle thread that when the needle loop of the previous stitch is dropped from the looper by the backward movement of the looper, to pull this needle loop up close to the work, which gets it out of the way of the next forward 15 movement of the looper, and also aids materially in the final setting of the stitch. This drawing up of the needle loop is accomplished by the down stroke of the needle, and, therefore, there is more or less lateral 20 strain on the needle during the drawing up of this previous needle loop.

The present machine contemplates the placing of the needles in a line, which, while diagonal to the line of feed, is as near as possible to a line at right angles to the line of feed. This necessitates the using of comparatively thin loopers and small needles. Furthermore, any material deflection in the needle which co-operates with one looper, 30 may cause the same to be interfered with by the next adjacent looper.

The present invention contemplates the providing of needle guards which co-operate with each of the needles and prevent any side movements of the needles at this time, when the needles are under strain in drawing 35 up the shed needle loops.

The invention also contemplates a needle guard for each needle, which will prevent the needle from being deflected so as to be struck by the looper, and, therefore, the loopers may be set so as to move very close to the needles, where a needle guard of this kind is used.

As herein shown, the needle guards are mounted upon the looper carrier and partake of all the movements of the loopers. That is, the needle guards are moved back and forth, and are also moved laterally when the looper is given its needle-avoiding movement. The needle guards consist of a plurality of upwardly projecting parts forming spaced walls, between which the needles may enter.

Referring more in detail to the needle guards, the same consist of a carrier or support having a projecting member 17 at the rear side thereof and a projecting member 18 at the front side thereof. Between these 60 projecting members 17 and 18 are two pro-

jecting members 19 and 20. The projecting member 19, as herein shown, is formed in two parts 21 and 22, while the projecting member 20 is likewise formed in two parts 23 and 24. The projecting member 21 is in 70 advance of the projecting member 22. The part 21 of the projecting member 19 and the projecting member 17 serve as a needle-guard for the left-hand needle, as viewed in Figs. 4 and 6 of the drawings. The projecting 75 member 17 guards the needle when the loop is being shed from the looper and prevents its deflection upon the drawing up of the threads, as shown in Fig. 7. The part 21 guards the needle when the looper is moving forward into the needle loop and prevents its deflection into the path of the needle. The part 22 of the projection 19 and the part 23 of the projection 20 form a needle guard for the intermediate needle and the part 24 of the projection 20 and the projection 18 form a needle guard for the right-hand needle, as shown in Figs. 4 and 6. These guards operate independently upon their respective needles and serve to prevent the deflection of the needle during the drawing up of the needle loops when they are shed from the looper and also prevent the deflection of the needles during the feed. These needle guards also prevent the deflection of the needles into the path of the loopers at the time when the loopers are moving forward into the needle loops.

The members 21 and 22 and also 23 and 24, as herein shown, are formed integral, for the reason that the needles are brought comparatively close together, as viewed in a direction transverse to the line of feed. From certain aspects of the invention, however, it will be seen that these parts may be made separate; and also from certain aspects of the invention only one pair of projecting members may be used with a single needle. It will be seen, therefore, that with each needle there is a pair of projecting members which are spaced and which form a needle guard for the needle. These projecting members partake of all the movements of the looper which co-operates with the needles, and first one wall of the projecting members and then the other wall must serve as a needle guard to properly hold the needle in its normal path. The space between the projecting members serves as a clearance space for the needle. These projecting members for each needle, therefore, form a needle guard and said projecting members constitute means for engaging the needle on the rear side thereof, on both forward and return strokes of the looper.

By the rear side of the needle throughout the description and claims, I have reference to the rear face of the needle, as viewed by the operator.

It is obvious that minor changes in the 130

details of construction may be made, without departing from the spirit of the invention, as set forth in the appended claims.

Having thus described our invention, what we claim as new and desire to secure by Letters Patent, is:—

1. A sewing machine including in combination a needle, a looper, a needle guard moving with the looper and having two spaced walls adapted to engage the needle, and means for moving said needle guard whereby one wall engages the rear face of the needle on its downward movement, and the other wall engages the rear face of the needle on its upward movement.

2. A sewing machine including in combination, a needle, a looper movable into and out of the needle loop, and laterally to avoid the needle, a needle guard moving with the looper, and means for operating it to engage the needle on the rear face of the latter in both its movements.

3. A sewing machine including in combination, a needle, a needle guard therefor, and means for operating it to cause the needle in a downward movement to be guided on its rear face by one face of the guard and in its upward movement to be guided on said rear face by another face of the guard.

4. A sewing machine including in combination, a feeding mechanism, a needle, means for reciprocating the needle, a looper moving substantially at right angles to the line of feed, a needle guard, and means for causing said needle guard to engage the rear side of the needle on both the upward and downward strokes of the needle, said needle guard having a movement transverse to the line of feed.

5. A sewing machine including in combination, a feeding mechanism, a needle, means for reciprocating the needle, a looper moving substantially at right angles to the line of feed into and out of the needle loop, and moving laterally to avoid the needle, a needle guard, and means for causing said needle guard to engage the rear side of the needle on both the upward and the downward strokes of the needle, said needle guard being connected to and movable with the looper.

6. A sewing machine including in combination, a feeding mechanism, a needle, a looper movable transversely to the line of feed, means for moving the looper into and out of the needle loop and for giving the looper a needle-avoiding movement, a needle guard movable transversely of the line of feed and having means for engaging the needle on both the upward and downward strokes of the needle.

7. A sewing machine including in combination, a feeding mechanism, a needle, a looper movable transversely to the line of

feed, means for moving the looper into and out of the needle loop and for giving the looper a needle-avoiding movement, a needle guard movable transversely of the line of feed and having means for engaging the needle on both the upward and downward strokes of the needle, and means for moving the needle guard with the looper.

8. A sewing machine including in combination, a feeding mechanism, a needle, a looper movable transversely to the line of feed, means for moving the looper into and out of the needle loop and for giving the looper a needle-avoiding movement, a needle guard movable transversely of the line of feed and having means for engaging the needle on both the upward and downward strokes of the needle, and means whereby the needle guard is connected to the looper, so as to partake of all the movements of the looper.

9. A sewing machine including in combination, a needle, means for reciprocating the needle, a looper coöperating with the needle, a needle guard having laterally spaced projecting members, one of which engages the needle on its rear face on its downward movement and the other of which engages the needle on said rear face on its upward movement.

10. A sewing machine including in combination, a needle, means for reciprocating the needle, a looper coöperating with the needle, a needle guard having spaced projecting members, one of which engages the needle on its rear face on its downward movement, and the other of which engages the needle on said rear face on its upward movement, and means for moving the needle guard in timed relation with the looper.

11. A sewing machine including in combination, a needle, means for reciprocating the needle, a looper coöperating with the needle, a needle guard having spaced projecting members, one of which engages the needle on its rear face on its downward movement, and the other of which engages the needle on said rear face on its upward movement, and means for connecting the needle guard to the looper, whereby said needle guard partakes of all the movements of the looper.

12. A sewing machine including in combination, a plurality of spaced needles, a looper coöperating with each needle, a needle guard for each needle comprising spaced projecting members, one of which engages the needle on its rear face on its downward stroke, and the other of which engages the needle on said rear face on its upward stroke.

13. A sewing machine including in combination, a plurality of spaced needles, a looper coöperating with each needle, a needle guard for each needle comprising spaced projecting members, one of which engages the needle on its rear face on its downward

stroke, and the other of which engages the needle on said rear face on its upward stroke, said needle guards being connected to and partaking of all the movements of the loopers.

14. A sewing machine including in combination, a feeding mechanism, a plurality of needles arranged in a line diagonal to the line of feed, a looper for each needle, a looper carrier on which said loopers are mounted, means for moving said carrier so that said loopers are caused to move in a path transverse to the line of feed and laterally thereof to avoid the needle, a plurality of needle guards, one for each needle, including spaced walls, one of which engages the needle on its downward movement, and the other of which engages the needle on its upward movement, said needle guards being mounted upon said looper carrier, whereby the needle guards partake of all the movements of the looper.

15. A sewing machine including a needle, means for operating said needle, a needle guard, a support for said needle guard,

means for moving said guard so as to engage the rear face of the needle on its downward movement, and means for swinging said guard across the path of its forward movement to engage the rear side of the needle on its upward movement.

16. A sewing machine including a needle, means for operating said needle, a needle guard having spaced vertical needle guiding walls, a support for said needle guard, means for moving the needle guard so as to position one of the guiding walls for engagement with the rear face of the needle on its downward stroke and for swinging said needle guard across the path of its forward movement to cause the other needle guiding wall to engage the rear face of the needle on its upward movement.

In testimony whereof we affix our signatures, in presence of two witnesses.
